JOSEPH KRÁLIK, OF BELLEVILLE, ILLINOIS.

BUFFER FOR VESSELS.

1,086,184.

Specification of Letters Patent.

Patented Feb. 3, 1914.

Application filed April 15, 1913. Serial No. 761,401.

To all whom it may concern:

Be it known that I, JOSEPH KRÁLIK, a subject of the King of Hungary, residing at Belleville, in the county of St. Clair and 5 State of Illinois, have invented certain new and useful Improvements in Buffers for Vessels, of which the following is a specification.

This invention relates to buffers for vessels, and the primary object of my invention is to provide the bow of various kinds of vessels and boats with novel buffers that will prevent the bow of a boat from being crushed or injured by contacting with ice- 10 bergs, floating debris, wharves and vessels.

Another object of this invention is to provide the bow of a vessel with a plow or deflector that wards off ice-bergs and floating debris to that extent as not to retard 15 progress of a vessel.

A further object of this invention is to provide simple, inexpensive and durable buffers for the bow of a vessel that occupy a comparatively small space and do not interfere with the general operating mechanism 20 of the vessel.

With the above and other objects in view the invention resides in the novel construction, combination and arrangement of parts 25 to be hereinafter specifically described and then claimed.

Reference will now be had to the drawing, wherein:—

Figure 1 is a side elevation of a portion of 30 a vessel provided with the buffers, and Fig. 2 is a horizontal sectional view of the same.

Further describing my invention in detail with reference to the drawing, wherein like numerals denote corresponding parts 35 throughout: 1 denotes the hull of a vessel having the bow 2 thereof provided with a plurality of vertical parallel uprights or bearings 3 and slidably mounted in these uprights are buffer rods 4. The rods 4 extend 40 through bearings 5, secured, as at 6, to the bow of the vessel. The buffer rods 4 have the inner ends thereof provided with collars 7 and the outer ends with buffer heads 8 that are made of a yieldable material, as hard rubber. The hard rubber is 45 preferably set in the outer ends of the rods 4 and in lieu of hard rubber I can use wood or a material softer than the bow of the vessel.

50 The buffer rods 4 between the uprights 3

are provided with collars 9 and encircling said rods, between the uprights 3 and the collars 9 are coiled compression springs 10. The tension of these springs is sufficient to hold the collars in engagement with the uprights, but when the buffer heads 8 encounter an obstruction the buffer rods yield and further compress the springs 10.

In practice it is preferable to arrange the buffers one above the other with the uppermost buffer of greater length than the lower buffer, whereby the upper buffer will be brought into action first.

Associated with the buffers is a plow or deflector 11 that is riveted or otherwise connected, as at 12 to the bow of a vessel below the lowermost buffer, this plow or deflector warding off such floating matter that cannot be controlled by the buffers.

It is obvious that additional buffers can 55 be located on the sides of the vessel, at the bow thereof or at such places throughout the vessel that are liable to be injured by collision.

What I claim is:—

1. The combination with the hull of a vessel, of a series of vertically disposed parallel uprights arranged in and centrally of the bow thereof, a pair of vertically alining bearings secured to the outer side of the bow centrally thereof, superposed buffer rods slidably mounted in said bearings and uprights and having their outer ends provided with heads, the head of the upper rod being normally projecting beyond the head of the lower rod, spaced collars secured to said buffer rods capable of engaging said uprights to arrest outward movement of said rods, and independent coiled compression springs encircling said buffer rods between said collars and uprights for normally maintaining the buffer rods projected.

2. The combination with the hull of a vessel, of a series of vertically disposed parallel uprights arranged in and centrally of the bow thereof, a pair of vertically alining bearings secured to the outer side of the bow centrally thereof, superposed buffer rods slidably mounted in said bearings and uprights and having their outer ends provided with heads, the head of the upper rod being normally projecting beyond the head of the lower rod, spaced collars secured to said buffer rods capable of engaging said uprights to arrest outward movement of

said rods, independent coiled compression springs encircling said buffer rods between said collars and uprights for normally maintaining the buffer rods projected, and a 5 downwardly inclined plow arranged below the lower of said rods and projecting forwardly from said bow.

In testimony whereof I affix my signature in presence of two witnesses.

JOSEPH KRÁLIK.
